UNITED STATES PATENT OFFICE.

HARVEY F. POPE, OF YORK, NEBRASKA.

DESIGN FOR A PATRIOTIC EMBLEM OR SIMILAR ARTICLE OF MANUFACTURE.

51,844.

Specification for Design.

Patented Mar. 5, 1918.

Application filed January 5, 1918. Serial No. 210,571. Term of patent 3½ years.

To all whom it may concern:

Be it known that I, HARVEY F. POPE, a citizen of the United States, residing at York, in the county of York and State of Nebraska, have invented a new, original, and ornamental Design for a Patriotic Emblem or Similar Article of Manufacture, of which the following is a specification, reference being had to the accompanying drawing, forming part thereof.

The figure is a perspective view of a patriotic emblem or similar article of manufacture embodying my design.

I claim:

The ornamental design for a patriotic emblem or similar article of manufacture, as shown.

HARVEY F. POPE.

Witnesses:

W. W. WYCKOFF,

C. E. CALLENDER.
